UNITED STATES PATENT OFFICE.

WARD S. IRELAND, OF ST. LOUIS, MISSOURI, AND WALTER E. LIPPERT, OF CINCINNATI, OHIO, ASSIGNEES, BY DIRECT AND MESNE ASSIGNMENTS, TO NATIONAL SHORT-HAND MACHINE COMPANY, OF ST. LOUIS, MISSOURI, A CORPORATION OF DELAWARE.

TYPE-WRITING MACHINE.

1,316,840.

Specification of Letters Patent. Patented Sept. 23, 1919.

Application filed November 18, 1916. Serial No. 132,066.

To all whom it may concern:

Be it known that we, WARD S. IRELAND and WALTER E. LIPPERT, citizens of the United States of America, residents, respectively, of the city of St. Louis, State of Missouri, and of Cincinnati, in the county of Hamilton, State of Ohio, have invented certain new and useful Improvements in Type-Writing Machines, of which the following is a full, clear, and exact description, reference being had to the accompanying drawings, forming a part of this specification.

Our invention relates to improvements in typewriting machines, and more particularly to paper feeding mechanism adapted for use in shorthand machines.

One of the objects of the invention is to produce a strong, simple and accurate paper feeding device adapted to coöperate with the finger keys of a shorthand machine, and adapted to advance the paper a fixed distance during each key operation. To insure the desired accuracy, we preferably use a strip of paper having marginal perforations which are formed at regular intervals throughout the length of the paper; and the paper feeding device preferably includes feed wheels having peripheral teeth adapted to enter the perforations. The feed wheels advance a predetermined distance during each key operation, and since these wheels are interlocked in the perforated paper, the action of the paper feeding device is absolutely positive; the paper being positively advanced a fixed distance during each feeding operation. An accurate paper feeding device of this kind is particularly adapted for use in a shorthand machine wherein the paper is to be fed step by step (line by line) in response to the key operations.

The preferred form of the invention includes a shearing device for cutting the paper into uniform sheets after it passes from the paper feeding device. The object is to cut the paper at regular intervals and at points midway between lines of reading matter. Owing to its accuracy, our paper feeding device will feed the paper in such a manner that the cutting action will take place at the predetermined points between the lines, and this is very important, for if the action of the paper feeding device was unreliable or inaccurate, the shearing device

would be liable to cut through a line of 5 characters instead of cutting between the lines. A further advantage of the new feeding device is that it is well adapted to pull the paper along a paper straightening device, so as to uncurl or straighten the paper 60 before feeding it from the machine.

With the foregoing and other objects in view the invention comprises the novel construction, combination and arrangement of parts hereinafter more specifically described 65 and illustrated in the accompanying drawings wherein is shown the preferred embodiment of the invention, however, it is to be understood that the invention comprehends changes, variations and modifications 70 which come within the scope of the claims hereunto appended.

Figure I is a plan view, partly in section, illustrating a shorthand machine embodying the features of our invention. 75

Fig. II is a longitudinal section of the machine shown in Fig. I.

Fig. III is a vertical section illustrating the printing and paper feeding devices.

Fig. IV is a detail view showing one of 80 the paper feeding wheels and the presser member associated therewith.

Fig. V is a fragmentary view of the means for straightening the paper.

Fig. VI is a vertical section taken approximately on the line VI—VI, Fig. III. 85

Fig. VII is a horizontal section showing the universal bar, the key levers which operate said universal bar, and a portion of the ribbon feeding mechanism which is 90 driven by said universal bar.

Fig. VIII is a section taken approximately on the line VIII—VIII, Fig. VII.

To illustrate the preferred form of the invention, we have shown a shorthand machine provided with a housing 1, a type holder 2 arranged in said housing (Figs. I, II and III) a type bar 3 secured in said type holder, and an inking ribbon 4 adjacent the line of type on said type bar 3. 100 The paper passes from a supply roll A, over a roller 5, under and partially around a roller 5', in front of and over a roller 6, and then to the paper feeding device whereby it is unwound from the roll and fed 105 through an opening 7 at the rear of the machine, see Fig. II.

The key actuated devices preferably in-

clude a series of angular levers each having an upwardly extending arm 8 at its front end (Fig. II) and a character key 9 at the upper end of said arm. Any suitable short-hand code may be used, and, if desired, the keys may be provided with characters corresponding to the line of type characters on the type bar 3. Each of the key levers includes an arm 10 extending rearwardly from its arm 8, and an arm 11 extending upwardly from the rear portion of said arm 10. The series of key levers is pivotally supported by a pivot member 12 located at the junctions of the lever arms 10 and 11. The upper end of each lever arm 11 is provided with a forwardly extending printing hammer 13 which lies adjacent the type 3, as shown most clearly in Figs. I and II. Restoring springs 14 (Fig. II) tend to retain the key levers in engagement with an abutment 15.

When one of the finger keys 9 is depressed, the key lever associated therewith turns about the axis of pivot members 12 and a printing hammer 13 moves toward the type 3, thereby forcing the paper and inking ribbon toward the type and printing one of the type characters on the paper. The key levers may be operated independently of each other, or any desired number of key levers may be operated simultaneously.

The universal bar associated with the key levers includes a transverse abutment holder 18 (Figs. II, III and VII) arranged in front of the series of lever arms 11, and provided with a yieldable abutment 19 which engages all of said lever arms 11. The universal bar also includes a pair of arms 20 and 21 pivotally supported by the pivot member 12, arranged on opposite sides of lever arms 11, and secured near their upper ends to the transverse abutment holder 18. 22 designates a connecting member uniting the arms 20 and 21 of the universal bar, said connecting member being located at the rear of lever arms 11. 23 designates a restoring spring (Figs. II and III) tending to retain the universal bar in the position shown in the drawings. The transverse abutment 19, forming part of the universal bar structure, is so arranged that the universal bar will move in response to movements of any one of the key levers.

The inking ribbon 4, which travels between the type bar 3 and printing hammers 13, is preferably a continuous strip of material (Fig. I) passing around guide spools 24, and fitted to a feed spool 25, the latter being fixed to a vertical shaft 26. The means for driving the feed spool 25 comprises a ratchet wheel 27 fixed to the shaft 26, an oscillatory pawl arm 28 loosely fitted to said shaft 26 and provided with a pawl 29 (Fig. VIII) which engages the ratchet wheel 27. A yieldable link 30, in

the form of a helical spring, connects the universal bar to the pawl arm 28, see Figs. I and VII. During each key operation, the universal bar oscillates about the axis of pivot member 12, and a corresponding movement is imparted, through the medium of yieldable link 30, to the oscillatory pawl arm 28, thereby advancing the ratchet wheel 27 one step. This ratchet wheel is secured to the vertical shaft 26, so that the ribbon feeding spool 25 which is fixed to said shaft, will advance one step in response to each key operation.

The paper feeding device preferably comprises a rotatable shaft 32, a pair of feed wheels 33 and 34 fixed to said shaft, a ratchet wheel 35 fixed to the feed wheel 34, and a pawl carrier 36 loosely secured to said shaft. 37 designates a pawl pivoted to the pawl carrier 36 (Fig. III), and 38 designates a spring connecting said pawl to the pawl carrier. The spring 38 tends to force the pawl into engagement with the ratchet wheel 35, as shown by dotted lines in Fig. III. The arm 21 of the universal bar is provided with an extension 39 (Figs. III and VI) which cooperates with an arm 40 on the pawl carrier 36. A spring 41 secured to the universal bar, forces the arm 40 into engagement with the universal bar extension 39, said arm 40 being provided with a pad which bears against said extension as seen in Fig. III. The arm 40, extending from pawl carrier 36, is so arranged between the spring 41 and universal bar extension 39, that the pawl carrier will partake of the movements of the universal bar. It will now be understood that the pawl carrier 36, as well as the universal bar, is under the control of the key levers, and that the pawl carrier is adapted to oscillate in response to movements of said key levers.

When a key is depressed, or when several keys are depressed simultaneously, the universal bar moves forwardly about the axis of the pivot member 12, and the pawl carrier 36 turns about the axis of shaft 32 so as to advance the ratchet wheel 35 one step, thereby turning the feed wheels 33 and 34 to unwind the paper and advance it one step. At the end of the paper feeding operation, the printing hammer or hammers 13 force the paper and inking ribbon toward the type to print the selected character or characters. Thereafter, the universal bar and key lever or levers, return to the positions shown in the drawings, and during this movement the paper feeding pawl 37 moves idly along the ratchet wheel 35. To prevent the retrograde movement, the shaft 32 is provided with a ratchet wheel 35' (Fig. I) and a pawl 37' is fitted to said ratchet wheel.

To insure an absolutely positive feeding

action, the margins of the strip of paper are preferably perforated as shown in Fig. I to receive the teeth which project from the periphery of the feed wheels 33 and 34. 5 These teeth are preferably tapered, as shown in Fig. II so that they will enter the perforations and mesh with the paper without tearing or otherwise mutilating the paper. The printing device is arranged to print 10 the shorthand characters at points between the perforated margins of the paper.

To prevent the paper from becoming disengaged from the feed wheels during the paper feeding operations, the paper 15 feeding device preferably includes a pair of presser arms 45, pivotally supported by stationary arms 46 and provided with grooves 47 (Fig. VI) for the reception of the teeth on the feed wheels. These presser 20 arms 45 engage the paper at points on opposite sides of the teeth on the feed wheels, so as to positively retain the paper in engagement with said wheels.

Each presser arm 45 is preferably provided with two notches 50 and 51 (Fig. IV) adapted to receive a spring pressed detent 52. When the pressing device occupies its operative position (Fig. IV) each presser member 45 is retained in engagement with 30 the paper by a detent 52 which lies in notch 50. In applying a new roll of paper to the machine, the presser members 45 are shifted away from the feed wheels to an inoperative position wherein they will permit the paper 35 to be fed, by hand, over the feed wheels. At this time, each presser member 45 is retained in its inoperative position by a detent 52 which then lies in a notch 51.

The means for straightening the paper 40 preferably comprises a roller 53, journaled in the presser members 45, and provided with an annular rib 53' adapted to enter an annular groove 54' in a roller 54. The roller 54 preferably lies between the feed 45 wheels 33 and 34, and it is rotatably supported by bearing members 55. Since the paper is firmly coiled around the axis of the supply roll, it tends to return to a curly condition after passing from the roll. However, when the paper passes between the 50 rollers 53 and 54 it is uncurled or straightened by the creasing action which takes place at said rolls. The middle portion of the strip of paper is forced into groove 54' by the annular rib 53', thus forming a reinforcing rib or ridge which stiffens the paper and prevents it from recurring.

After passing from the straightening device, the paper advances step by step to a 55 shearing device, whereby it is cut into small uniform sheets. The shearing device we have shown (Fig. II) includes a stationary blade 57 and a movable blade 58. The movable blade may be operated by any suitable automatic mechanism. The paper advances a

fixed distance during each key operation, and the shearing device is so located that it will cut the paper between two lines of reading matter.

When the upper portion of the universal 70 bar moves forwardly it positively pushes the pawl carrier 36 (Fig. III) to insure the desired positive paper feeding action, and during the return movement of the universal bar, the pawl carrier is forced back- 75 wardly through the medium of spring 41, the latter being secured to the universal bar. This spring 41 retains the pawl carrier in engagement with the universal bar, thereby preventing noisy hammer blows 80 which would occur if one of these parts was permitted to strike the other. The axes of the universal bar and pawl carrier lie in different planes, and these parts therefore slide on each other during the paper feeding operations. The spring 41 yields freely 85 to permit a movement of this kind. Furthermore, the noiseless joint at the junction of the universal bar and pawl carrier is not impaired by wear at the point where said 90 parts engage each other. Another advantage of this substantially universal joint, is that the spring 41 will yield to compensate for inaccuracies in the dimensions or location of the parts with which it is associated. 95

The printing elements herein shown are claimed in an application for patent filed by W. S. Ireland on Nov. 18, 1916, Serial No. 132,076. The key lever guide is claimed in an application filed by W. S. Ireland 100 and W. E. Lippert on Nov. 18, 1916, Serial No. 132,077. The universal bar is claimed in an application filed by W. S. Ireland and W. E. Lippert on Nov. 18, 1916, Serial No. 132,078. The ribbon feeding mechanism 105 and certain elements associated therewith are claimed in an application filed by W. S. Ireland on Nov. 18, 1916, Serial No. 132,075. The automatic cutting device is claimed in an application filed by W. S. Ireland on 110 Nov. 18, 1916, Serial No. 132,071. The paper straightening device is claimed in an application filed by W. S. Ireland on Nov. 18, 1916, Serial No. 132,070.

We claim:—

1. In a typewriting machine adapted to receive a strip of paper having perforated margins, a paper feeding device comprising a rotatable shaft, a pair of feed wheels secured to said shaft, said feed wheels having 120 peripheral teeth adapted to enter said perforated margins, a ratchet wheel secured to said shaft, a pawl arm for driving said ratchet wheel, and a universal bar for operating said pawl arm.

2. In a typewriting machine adapted to receive a strip of paper having perforated margins, a paper feeding device comprising a rotatable shaft, a pair of feed wheels secured to said shaft, said feed wheels hav- 130

ing peripheral teeth adapted to enter said perforated margins, a ratchet wheel secured to said shaft, a pawl arm for driving said ratchet wheel, said pawl arm being loosely mounted on said shaft, and a universal bar for operating said pawl arm.

3. In a typewriting machine adapted to receive a strip of paper having perforated margins, a paper feeding device including 10 feed wheels adapted to enter the perforations at said margins, a presser member for retaining the paper in engagement with the teeth of said feed wheels, a pivotal support for said presser member, said presser member being movable toward and away from said feed wheels, and a spring pressed detent for holding said presser member in its operative position.

4. In a typewriting machine adapted to 20 receive a strip of paper having perforated margins, a paper feeding device including feed wheels adapted to enter the perforations at said margins, a presser member for retaining the paper in engagement with said feed wheels, a pivotal support for said presser member, said presser member being movable away from said feed wheels, and a spring pressed detent for holding said presser member in either its operative or in- 30 operative position.

5. In a typewriting machine adapted to receive a strip of paper having perforated margins, a paper feeding device including feed wheels adapted to enter the perforations at said margins, a presser member for retaining the paper in engagement with the teeth of said feed wheels, a pivotal support for said presser member, said presser member being provided with two notches, and a 35 spring pressed detent adapted to enter either of said notches so as to hold said presser member in either its operative or in- 40 operative position.

6. In a typewriting machine adapted to 45 receive a strip of paper having perforated margins, a printing device for printing on the paper at points between the perforations, a paper feeding device including feed wheels having peripheral teeth adapted to enter the

perforations at opposite sides of the printed matter, and a paper straightening device associated with said feed wheels, said paper straightening device being effective upon the operation of said feed wheels. 50

7. In a typewriting machine adapted to 55 receive a strip of paper having perforated margins, a printing device for printing on the paper at points between the perforations, a paper feeding device including feed wheels having peripheral teeth adapted to enter the 60 perforations at opposite sides of the printed matter, and a paper straightening device between said feed wheels, said paper straightening device being effective upon the operation of said feed wheels. 65

8. In a typewriting machine adapted to receive a strip of paper having perforated margins, a printing device for printing on the paper at points between the perforations, a paper feeding device including feed wheels 70 having peripheral teeth adapted to enter the perforations at opposite sides of the printed matter, and a paper straightening device arranged to engage the paper at points between said perforations. 75

9. A typewriting machine having a paper feeding device including a key actuated universal bar, and a paper feeding device operable by said universal bar, said paper feeding device including a pivotally supported 80 pawl arm, said universal bar being adapted to engage said pawl arm to positively move the latter in one direction, and a spring for returning said pawl arm in response to a corresponding movement of the universal 85 bar, said spring being arranged to retain said pawl arm in engagement with said universal bar.

10. A typewriting machine having a universal bar, keys for operating said universal 90 bar, and a paper feeding device including a pawl carrier slidably fitted to said universal bar, and a spring for retaining said pawl carrier in engagement with said universal bar.

WARD S. IRELAND.
WALTER E. LIPPERT.
